(57) CLAIM

The ornamental design for healthcare equipment, as shown and described.

DESCRIPTION

FIG. 1 is a perspective front, top and left side view of healthcare equipment showing my new design;

FIG. 2 is a perspective rear, top and left side view thereof;

FIG. 3 is a front view thereof;

FIG. 4 is a rear view thereof;

FIG. 5 is a bottom view thereof;

FIG. 6 is a top view thereof;

FIG. 7 is a right side view thereof; and,

FIG. 8 is a left side view thereof.

The ornamental design which is claimed is shown in solid lines in the drawings.
